UNITED STATES PATENT OFFICE.

GEORGE H. LELAND, OF DAYTON, OHIO, ASSIGNOR OF ONE-HALF TO THE LELAND ELECTRIC COMPANY, OF DAYTON, OHIO, A CORPORATION OF OHIO.

DYNAMO-ELECTRIC MACHINE.

Application filed October 5, 1921. Serial No. 505,454.

This invention relates to improvements in dynamo electric machines, having particular reference to single-phase alternating current motors of the repulsion-starting and induction-running type, and being a modification of the improvements which form the subject matter of my copending application for patent Serial No. 425,832, filed November 22, 1920.

In my earlier invention, above referred to, the improvements consist essentially in providing a centrifugal element mounted in operative relation with the armature shaft to effect short-circuiting of the armature when the motor attains operating speed, the centrifugal element, in the preferred form illustrated, consisting in a plurality of weights operable radially outwardly of the armature shaft into contact with the commutator segments, thus to form the short-circuit, and operable radially toward the shaft to disrupt the short-circuit when the motor falls below operating speed. An important feature of the invention which forms the subject matter of my earlier application consists in providing means for causing a wiping action of the weight elements, with increasing pressure on the contact surfaces as contact is made,—thus to obtain and maintain highly efficient conditions of the motor in its adaptability to change from repulsion to induction operation.

The present invention provides means, as a further step, for maintaining these highly desirable conditions of operation in motors of this type, the improvements of the invention consisting in means for retaining the weight elements radially aligned one with another,—thus to insure under all conditions the full wiping, pressure relation between the contact elements as the short-circuit is made or broken.

It is an object of the present invention to retain the simple construction and direct relation of parts, which are of outstanding merit in my invention of record referred to, and to adapt the present improvements to the earlier construction without material change in the arrangement of parts or their coordinated operation,—the whole purpose of the later modification being, as stated, to insure normal action of the short-circuiting elements without chance or possibility of inefficient operation.

In the accompanying drawings:

Fig. 1 is a detail view of a motor having my invention applied thereto, and showing the commutator and short-circuiting mechanism in section, taken on line 1—1 of Fig. 2;

Fig. 2 is a full end view of Fig. 1 having part of the mechanism broken away;

Fig. 3 is in two detail sectional views illustrating the short-circuiting elements in operative and inoperative relations;

Fig. 4 is in two detail views illustrating the weight elements detached, and

Fig. 5 is a diagrammatic view illustrating the direction of forces operative in the short-circuiting operation and in effecting the wiping, pressure contact action of the elements.

As here shown, the details of motor construction used for illustrating the invention consist of the armature shaft —1, rotor —2, commutator ring —3 and commutator segments —4, these parts being common to motors of the type illustrated and adapted in any suitable form for the practice of my invention.

The short-circuiting mechanism, as here shown, consists of a plurality of wedge-shaped weights —5 arranged radially around the commutator shaft between flat, radial weights —6 which serve to divide the weights —5 into groups,—there being, as here shown, six groups of weights with nine weights —5 and one weight —6 to each group. The weights are retained in their radial relation on shaft —1 by a coiled spring —7 which is arranged circumferentially around the assembled weights and acting, when the motor is at rest, to hold the weights in contact at their inner ends with shaft —1, the weights and spring —7 being retained against outward axial displacement relative to shaft —1 by a disc —8 and spring lock-ring —9 set in an annular groove —10 of the shaft, disc —8 being otherwise free to rotate on the shaft, thus compensating for the rotating momentum of the weights and effecting smooth operation of the motor.

As best shown in Fig. 2 of the drawings, retaining disc —8 has a series of radial slots —11, and each weight —6 has a shoulder —12 adapted to fit freely in one of the slots —11, the slot thus acting as a guide for the weight in its radial movements and acting to prevent rotative or lateral movement of

weights —6 relative to the disc, and also to reduce lateral movement of weights —5 to such extent that lateral displacement of weights will be negligible and the best 5 contact relations between the weights and the commutator segments will be maintained.

As best shown in Fig. 3 weights —5 and —6 are each provided with a lower inward 10 projection —13 which has free sliding relation in a depression —14 in the outer face of the commutator ring —3, and an upper inward projection —15 which has sliding contact relation with the commutator segments —4 under inward, lateral pressure 15 exerted thereon by spring —7, the outer ends of the weights being formed at an angle downwardly and outwardly, as illustrated in the detail figures, thus the pressure of the 20 spring at the contact points —15 of the weights will be inwardly at an angle to the radial plane of operation of the weights, with the result that contact between the 25 weights and commutator segments will be made by wiping action of the weights under increasing pressure as the weights move outwardly under centrifugal force generated 30 therein by rotation of the motor, the direction of forces being indicated in Fig. 5, and 35 as will be readily understood from the detailed description, the weights being equally grouped and retained in approximate radial planes, the short-circuiting contact will be made between each weight and segment 40 without variation as to the relative movement therebetween, or variations so slight 45 that the effect on the operation of the motor will be negligible.

Motors embodying my invention in the 40 earlier construction of record herein referred to, have proved in tests to be highly efficient and are being manufactured in quantities, and tests made of the present invention show results which evidence the utmost 45 dependability and effectiveness of the short-circuiting mechanism.

Having described my invention, I claim:

1. In short-circuiting mechanism for single-phase, alternating current motors and in 50 combination with the armature and commutator thereof, a plurality of centrifugal elements arranged in groups circumferentially and radially relative to the armature shaft, and a spring element arranged 55 circumferentially and operable radially with the centrifugal elements and adapted to exert resistance thereon at an angle to their said radial movement whereby pressure is provided for 60 establishing wiping contact between said centrifugal elements and the commutator segments.

2. In a short-circuiting mechanism for single-phase, alternating current motors and 65 in combination with the armature and com-

mutator thereof, a plurality of centrifugal elements arranged in equal groups, retained as to lateral displacement, and arranged circumferentially and radially relative to the armature shaft, and a spring element 70 arranged circumferentially and operable radially with the centrifugal elements and adapted to exert resistance thereon at an angle to their said radial movement whereby pressure is provided for establishing wiping 75 contact between said centrifugal elements and the commutator segments.

3. In short-circuiting mechanism for single-phase, alternating current motors and 80 in combination with the armature and commutator thereof, a plurality of centrifugal elements arranged in equal groups, retained as to lateral displacement by certain of the elements of each group, and arranged circumferentially and radially relative to the 85 armature shaft, and a spring element arranged circumferentially and operable radially with the centrifugal elements and adapted to exert resistance thereon at an angle to their said radial movement whereby pressure is provided for establishing wiping 90 contact between said centrifugal elements and the commutator segments.

4. In short-circuiting mechanism for single-phase, alternating current motors and 95 in combination with the armature and commutator thereof, a plurality of radial centrifugal elements arranged in equal groups circumferentially of the armature shaft and retained axially thereon by a disc having 100 a series of radial slots, certain of said elements being operable in said slots and acting to retain the elements of each group as to lateral displacement thereof, and a spring element arranged circumferentially and 105 operable radially with the centrifugal elements and adapted to exert resistance thereon at an angle to their said radial movement whereby pressure is provided for establishing wiping contact between said centrifugal elements and the commutator segments.

5. In short-circuiting mechanism for single-phase, alternating current motors and in combination with the armature and the 115 commutator thereof, a plurality of radial centrifugal elements arranged in equal groups circumferentially of the armature shaft and retained axially thereon by a disc 120 rotatably supported on the armature shaft and having a series of radial slots, certain of said elements being operable in said slots and acting to retain the elements of each group as to lateral displacement thereof, and a spring element arranged circumferentially and operable radially with the centrifugal elements and adapted to exert resistance 125 thereon at an angle to their said radial movement whereby pressure is provided for establishing wiping contact between said 130

centrifugal elements and the commutator segments.

6. In short-circuiting mechanism for single-phase, alternating current motors and in combination with the armature and the commutator thereof, a plurality of radial, wedge-shaped centrifugal elements arranged in groups circumferentially of the armature shaft, and retained axially thereon by a disc mounted on said shaft and having a series of radial slots, other radial centrifugal elements interposed between the groups of the wedge-shaped elements and operable in said slots to retain the elements of each group as to lateral displacement thereof, and a spring element arranged circumferentially and operable radially with the centrifugal elements and adapted to exert resistance thereon at an angle to their said radial movement whereby pressure is provided for establishing wiping contact between said centrifugal elements and the commutator segments.

7. In a short circuiting device for electric motors, a rotor shaft, a commutator mounted thereon, a retaining member slidably mounted on said shaft adjacent to said commutator, means for limiting the movement of said retaining member away from said commutator, an annular series of centrifugal weight members interposed between said commutator and said retaining member, operable radially to effect the short circuiting of the commutator, and a contractile band in rolling engagement with said weight members and arranged to simultaneously resist the outward movement of said weight members and maintain them in resilient sliding contact with the commutator, and to maintain said retaining member yieldingly in engagement with the means for limiting its movement.

8. A short circuiting device for electric motors, comprising in combination with a shaft and a commutator carried thereby, said shaft having a circumferential groove spaced from the face of said commutator, a retaining disc mounted on said shaft between said groove and said commutator and having a series of radial slots spaced one from the other, a lock ring seated in said groove and engaging said disc to limit the axial movement thereof with relation to said commutator, a series of weight elements mounted circumferentially of said shaft be-

tween said disc and said commutator and movable outwardly by centrifugal force, a part of said weight elements having projections slidably mounted in the respective slots in said disc, and a tension element acting on said weight elements to resist their outward movement and on said retaining disc to press the same against said lock ring.

9. A short circuiting device for electric motors, comprising in combination with a shaft and a commutator carried thereby, said shaft having a circumferential groove spaced from the face of said commutator, a retaining member mounted on said shaft between said groove and said commutator, a lock ring seated in said groove and engaging said retaining member to limit the axial movement thereof with relation to said shaft, a series of weight elements arranged circumferentially of said shaft between said retaining member and said commutator and movable outwardly by centrifugal force, and a tension element acting on said weight elements to resist their outward movement and on said retaining member to press the same against said lock ring.

10. A short circuiting device for electric motors comprising in combination with a shaft and a commutator carried thereby, said shaft having a circumferential groove spaced from the face of said commutator, a retaining member mounted on said shaft between said groove and said commutator, a lock ring seated in said groove and engaging said retaining member to limit the axial movement thereof with relation to said shaft, a series of weight elements arranged circumferentially of said shaft between said retaining member and said commutator and movable outwardly by centrifugal force, said weight elements having their outer ends inclined toward said retaining member and said shaft, and a contractile band engaging the inclined ends of said weight elements and said retaining member to resist the outward movement of said weight elements and to press the same toward said commutator, and acting on said retaining member to press the same against said lock ring.

In testimony whereof, I affix my signature.

GEORGE H. LELAND.
